UNITED STATES PATENT OFFICE.

GEORGE W. JACKSON, OF CHICAGO, ILLINOIS.

SUBMARINE PIER.

No. 916,159.

Specification of Letters Patent. Patented March 23, 1909.

Application filed May 5, 1908. Serial No. 430,982.

To all whom it may concern:

Be it known that I, GEORGE W. JACKSON, a citizen of the United States, and a resident of Chicago, in the county of Cook and State 5 of Illinois, have invented certain new and useful Improvements in Submarine Piers; and I do hereby declare that the following is a full, clear, and exact description thereof, reference being had to the accompanying 10 drawings, and to the numerals of reference marked thereon, which form a part of this specification.

This invention relates to an improved submarine foundation structure or pier for supporting a superstructure over a body of water, and the invention consists in the matters hereinafter set forth and more particularly pointed out in the appended claims.

Among the objects of my invention is to 20 provide a pier construction which may be quickly assembled at relatively small expense and which will afford a foundation of great strength to support a superposed load and to resist lateral stress due to the action of waves 25 or floating ice or to wind pressure against a structure supported thereon.

As shown in the drawings:—Figure 1 is a side elevation of a pier or foundation made in accordance with my invention. Fig. 2 is 30 an enlarged side elevation thereof, partially broken away. Fig. 3 is a side elevation of one of the panels constituting part of the shell of the pier. Fig. 4 is a horizontal section of said panel. Fig. 5 is a top plan view 35 of the pier with the filling omitted, showing one form of load supporting frame. Fig. 6 is a detail illustrating the manner of attaching strengthening and bracing rings to the piles constituting part of the pier. Fig. 7 is a detail section, taken on line 7—7 of Fig. 6. Fig. 40 8 is a detail section, taken on line 8—8 of Fig. 6. Fig. 9 is a horizontal plan view illustrating the manner of attaching the load carrying frame to the pier structure. Fig. 10 is a side view of the parts shown in Fig. 9. Fig. 11 is 45 a detail section, taken on line 11—11 of Fig. 9.

The submarine foundation or pier herein shown is adapted for use as the supporting foundation or pier of a marine aerial tramway, such as is shown in my concurrent application for U. S. Letters Patent filed of even date herewith, Serial No. 430,981, the load supporting frame at the top of said pier or foundation being arranged to support a tower 50 55 constituting part of such aerial tramway. It will be understood, however, that said pier

may be used for supporting other structures, such as cribs, bridges, light-houses and the like. By reason of the peculiar construction of the pier, however, it is peculiarly adapted 60 for use as supporting structures which are erected for temporary use, inasmuch as it is capable of being quickly constructed and installed at comparatively small expense, and the parts thereof may be reclaimed and used 65 for the same or other like purposes.

A pier made in accordance with my invention embraces a plurality of metal sheet piles 15 of any desired cross-section which are driven into the bottom of a lake or other 70 body of water about an area which the pier is to occupy, a plurality of sections or panels 16 stretched between and supported on said piles to inclose said area, and a body 18 of stone or other filling material which fills the 75 shell thus formed and which gives body or permanence to the pier to resist lateral stress brought thereon. The said piles 15 are driven a distance into the bottom beneath the body of water and are adapted to extend 80 at their upper ends a distance above the level of the water. As herein shown, said piles are driven to inclose a circular area to produce a circular pier, but the cross-sectional contour may be varied. The panels 85 or sections 16 which extend between and are connected to said piles constitute the wall of a cage like structure which contains and confines the mass filling, as the body 18 of stone. The said panels extend horizontally 90 from one pile to an adjacent pile and are adapted for interlocking and sliding connection at their ends with said piles in such manner that after the piles have been driven, the panels are placed between the piles, at 95 the upper ends thereof, and interlocked at their ends with said piles, and are afterward dropped downwardly between the piles to be supported vertically on the bottom beneath the body of water. The said 100 panels are shown as arranged in a plurality of horizontal sets or rows supported one upon the other. The construction of the panels which constitute the wall of said cage-like inclosure is shown more clearly in Figs. 105 3 and 4 and they are made as follows: As herein shown, said panels are of flexible construction. They comprise upper and lower chains 20, 20 and a plurality of laterally separated vertically parallel heavy planks or 110 bars 21 supported thereon. Said chains are provided at their ends with clips 22, 22 that

are constructed to engage the flanged margins of the piles 15 in such manner as to slide endwise of the piles but are laterally interlocked therewith. As herein shown, 5 the piles are of I-beam cross-section and the clips employed each comprises two plates 23, 23 which are bolted flatwise together and are formed at their outer ends to provide oppositely opening hooks 24, 24 which engage 10 over the oppositely directed flanges of the I-beam piles. The end links of said upper and lower panel chains engage with apertures in said clip plates. The manner of supporting the vertical, parallel planks or 15 bars 21 on the chains, as herein shown, is as follows: Alternate links 26 of the chains 20, 20 are made of sufficient dimensions to constitute holders to receive said bars 21, which latter are attached to said enlarged links or 20 holders by means of U-bolts 27. The closed parts of said U-bolts extend over or inclose the side members of the links at one side of each panel and the shanks of said bolts pass through said bars on opposite sides of the 25 other side members of said links or holders and through clips 28, 28 which fit over the adjacent sides of said links, as best shown in Fig. 4. The said piles 15 are tied together and braced at their upper ends by means of 30 interior, upper and lower rings 30, 31, which are herein shown as made of I-beam cross-section. The upper bracing and tying ring 30 is attached to the webs of the I-beam piles by means of bolts 32, and said ring is spaced 35 from said piles by means of channel shaped spacing fittings 33 through which said fastening bolts extend. Short spacing sleeves 34 are located between the free margins of said channel spacing fittings 33, through 40 which the fastening bolts extend, to impart the desired rigidity to the spacing fittings. The lower ring 31 is unattached to the piles, as herein shown, and constitutes merely a bracing ring to prevent inward collapsing of 45 the cage-like structure. Said lower bracing ring is suspended from the upper ring by means of chains or links 35 and is spaced from the piles by spacing fittings 36 which are attached to the webs of the said I-beam 50 bracing ring and extend outwardly therefrom for engagement with the webs of the piles.

In constructing a pier or foundation embodying my invention, two oppositely located piles 15, 15 may first be driven, they being set at the proper distance apart and properly alined with respect to each other and to the center of the proposed pier from the shore. Thereafter a pile may be located 60 and driven at each side of each pile thus driven, said piles being placed or located from the piles first driven by the use of suitable floating templets or the like. After the six piles have thus been placed and driven, the 65 curved bars or segments which make up the

lower spacing ring are fastened together to complete the ring and the ring is placed within the area partially surrounded by the driven piles. Said segments of the bracing ring may be handled, while the same is being assembled, upon suitable floating rafts and the assembled ring may be suspended from said rafts by the chains or links 35 until the upper binding or tying ring is placed and fastened to the piles. After the lower bracing ring is 70 assembled and placed in the manner described, the upper or tying ring is assembled and attached to the driven piles, after which the suspending links or chains 35 are attached to the upper ring to suspend the 75 lower ring therefrom. After the upper and lower rings have been thus placed the remaining piles are driven, said rings serving as convenient means to locate and guide the piles while being driven. After all of the 80 piles of the pier have been thus driven and the upper ring is fastened to the upper ends of all of the piles, the first or lower row of panels 16 are fitted to the piles; the said panels being lifted by any suitable lifting device 85 above the upper ends of the piles and the clips 21 engaged with the flanges of the piles, after which said panels are allowed to drop by gravity between the piles until they rest on the bottom beneath the body of water. 90 Thereafter the space inclosed by the first or lower row of panels is filled in with the filling material, after which another row of panels is dropped into place and the space inclosed thereby filled. These operations are 95 continued until all of the panels have been placed and the entire space inclosed by the cage or frame formed thereby filled with the filling material.

The pier is herein shown as adapted to support a tower, designated as a whole by 40, which may constitute one of a plurality of towers designed to support the tramway cable shown in my aforesaid application.

A frame is shown for connecting the base 110 of the tower with the pier, which is made and connected with the pier in the following manner: 41 designates, as a whole, a rectangular frame supported on said pier and made of angle bars, as herein shown. Said frame is 115 of such dimension that the four corners thereof extend slightly beyond the curved line of the cage-like shell or inclosure of the pier. The corners of said frame are supported on tangentially arranged, horizontal 120 supports 42, 42, each of which extends between the upper ends of two adjacent piles 15, 15 of the pier and are attached thereto. Said supports 42 each consists, as herein shown, of two parallel I-beams 43, 43, the 125 upper flanges of which are arranged horizontally and in the same plane to constitute broad supporting surfaces for the frame. Each pair of I-beam supports 42 are attached to two adjacent piles 15, 15 by angle brack- 130

ets 44, 44, the vertical members of which are attached to the webs of said I-beam piles and the horizontal members of which fit beneath and are attached to the lower flanges of said 5 supporting beams. The said brackets thus constitute means at the ends of said beams for joining or connecting the two beams of each support. The beams of each support 42 may be further connected or tied together 10 by bolts 45 extending transversely through the webs thereof and plates 46 attached to the lower flanges of the beams, as best shown in Fig. 11. Said load supporting frame 40 is connected with said supports 42 by means 15 made as follows: Attached to the under sides of said frame at the corners thereof are triangular plates 46', 46' which rest flat on the supports 42. The said triangular plates are attached to the members of the frame 41 by 20 bolts or rivets 48 which extend through the margins of said plates and through the horizontal flanges of the frame members. The inner margins of said plates are stiffened by reinforcing bars 49 which are riveted thereto. 25 The said triangular frame plates are shown as provided with slots 50, arranged diagonally with respect to the frame 41, downwardly through which extend bolts 51 which fasten the load supporting frame to the pier. 30 Said bolts extend downwardly through the spaces between the I-beam members of the supports 42 and through openings in the plates 46. Arranged at the opposite sides of each of said slots 50 are two parallel angle 35 bars 55 which are riveted to the plates 46 and against the vertical flanges of which the nuts of said bolts 51 bear.

The arrangement of the slots 50, through which the fastening bolts extend, transversely with respect to spaces between the beams of the support 42 affords means for angularly shifting the load supporting frame relatively to the central vertical axis of the pier or foundation. Such adjustment is 45 effected at a time when the nuts of the attaching bolts 51 are loosened, after which the nuts are tightened to rigidly fix said frame to the pier structure. The construction of the load supporting frame 41 and the 50 manner of supporting the same on the pier may be variously arranged to conform to the superstructure or load to be carried thereby. As herein shown, it is arranged to support the tower of an aerial tramway which carries 55 the tram cable and the traveling or pulling cable of such a tramway. The features of construction relating to the load carrying frame and the manner of adjusting the same on the pier is illustrated and claimed in my 60 aforesaid copending application.

If the panels or sections extending between and supported at their ends by the piles be made solid or more nearly solid than herein shown, the space inclosed by the 65 shell or wall may be filled with a concrete or

cementitious material, mixed or not with stones or other filling material, which, upon hardening, will form a solid or monolithic body which receives the load of the superstructure and is protected by the surrounding shell or wall. Moreover, the pier may be otherwise constructed to distribute the load of the superstructure partially or wholly upon that part of the pier within the surrounding shell or wall composed of the piles 70 and panels shown. The rings 30 and 31 serve to brace and tie together the piles after they have been driven and before the panels and filling material have been placed, thus preventing lateral pressure of waves or ice 75 bending or forcing the upper ends of the piles out of line. Said rings also serve to strengthen the completed structure to withstand lateral pressure. The flexible panels are advantageous inasmuch as their flexible 80 structure permits the ends thereof to be interlocked with the piles and the panels to slide down into place on said piles, notwithstanding slight variations of alinement of the piles. 90

It is obvious that I have provided a submarine pier or foundation which may be quickly installed and which possesses great strength for supporting a load and for resisting lateral stresses due to wave and ice action against the same. By reason of the fact that the said pier may be readily constructed at relatively small expense, and by reason of the fact that practically all the material used in shell of a temporary pier 95 may be reclaimed and used again for other or like purposes, the said construction is particularly adapted for use as a temporary foundation or pier. A pier embodying the essential features of the invention described 100 may, however, be constructed and employed for more permanent uses.

It will be understood that many changes other than those suggested may be made in the details of construction without departing 110 from the spirit of my invention and I do not wish to be limited to such details except as hereinafter may be made the subject of specific claims.

I claim as my invention:—

1. A submarine foundation or pier comprising piles driven into the bottom beneath a body of water around the area occupied by the pier, flexible panels or sections extending between and adapted for interlocking and 120 sliding connection at their ends with said piles longitudinally of the latter to constitute an inclosing shell or wall, and a mass of filling material filling the space inclosed by said shell or wall. 125

2. A submarine foundation or pier comprising piles driven into the bottom beneath a body of water around an area occupied by the pier, panels or sections extending between and adapted for interlocking and 130

sliding connection at their ends with said piles entirely from the upper ends of said piles to the bottom into which they are driven to constitute an inclosing wall or shell, and a mass of filling material filling the space inclosed by said wall or shell.

3. A submarine foundation or pier comprising piles driven into the bottom beneath a body of water around an area occupied by 10 the pier, panels or sections adapted for interlocking and sliding connection at their ends with said piles to constitute an inclosing wall or shell, each of said panels consisting of flexible strands or chains, and vertical, 15 laterally separated bars supported thereon, and a mass of filling material filling the space inclosed by said wall or shell.

4. A submarine foundation or pier comprising piles driven into the bottom beneath 20 a body of water around an area occupied by the pier, a plurality of horizontal, superposed rows of panels or sections extending between and adapted for interlocking and sliding connection at their ends with said 25 piles to constitute an inclosing wall or shell, and a mass of filling material filling the space inclosed by said wall or shell.

5. A submarine foundation or pier comprising piles driven into the bottom beneath 30 a body of water around an area occupied by the pier, panels or sections extending between said piles, each consisting of upper and lower chains having interlocking and sliding connection at their ends with said piles and a 35 plurality of vertical, laterally separated bars extending through and supported in the links of said chains, and a mass of filling material filling the space inclosed by the cage-like wall thus constructed.

40 6. A submarine foundation or pier comprising piles driven into the bottom beneath a body of water around an area occupied by the pier, means for rigidly connecting the piles at their upper ends, panels or sections 45 extending between and adapted for interlocking and sliding connection at their ends with said piles to constitute an inclosing wall

or shell, and a mass of filling material filling the space inclosed by said wall or shell.

7. A submarine foundation or pier comprising piles driven into the bottom beneath a body of water to inclose an area occupied by the pier, a tying ring inclosed by and attached to the upper ends of said piles, a plurality of panels extending between and having interlocking and sliding connection at their ends with said piles to constitute an inclosing wall or shell, and a mass of filling material filling the space inclosed by said wall or shell. 50

8. A submarine foundation or pier comprising piles driven into the bottom beneath a body of water to inclose an area occupied by the pier, a tying ring inclosed by and attached to the upper ends of said piles, a 55 bracing ring suspended from the tying ring, and a plurality of panels extending between and having interlocking and sliding connection at their ends with said piles to constitute an inclosing wall or shell, and a mass of filling material filling the space inclosed by said wall or shell. 60

9. A submarine foundation or pier comprising piles driven into the bottom beneath a body of water to inclose the area occupied 75 by the pier and extending above the water level, panels extending between and adapted for interlocking and sliding connection at their ends on said piles to constitute an inclosing wall or shell, the extreme upper ends 80 of said piers being arranged to receive the interlocking parts of said panels, a mass of filling material filling the space inclosed by said wall or shell, and a load supporting frame carried by the upper ends of said piles. 85

In testimony, that I claim the foregoing as my invention I affix my signature in the presence of witnesses, this 29th day of April A. D. 1908.

GEORGE W. JACKSON.
